UNITED STATES PATENT OFFICE.

HENRY F. LOOMIS, OF READING, PENNSYLVANIA.

EXHAUST DEVICE FOR INTERNAL-COMBUSTION ENGINES.

1,286,365.

Specification of Letters Patent. Patented Dec. 3, 1918.

Application filed November 14, 1917. Serial No. 201,927.

To all whom it may concern:

Be it known that I, HENRY F. LOOMIS, a citizen of the United States, residing at Reading, in the county of Berks and State of Pennsylvania, have invented certain new and useful Improvements in Exhaust Devices for Internal-Combustion Engines, of which the following is a specification.

My invention relates to means for facilitating the discharge of exhaust gases from internal combustion engines and particularly where the exhaust is baffled or muffled to reduce the noise of the explosion in the engine cylinders. My device, while applicable to all internal combustion motor vehicles, is particularly useful in aeroplanes. Heretofore aeroplane engines have not been muffled, as the back pressure exerted by the muffler on the cylinders has materially reduced the power so as to be decidedly objectionable. My device comprises means for causing suction at the discharge end of the exhaust conduit to more quickly free said conduit after each cylinder explosion and reduce or prevent back pressure. This suction device may be applied at the discharge end of any well known type of muffler, but is preferably employed in connection with my spirally arranged baffle plates located within the exhaust conduit. My invention is fully described in connection with the accompanying drawings and the novel features are pointed out in the claims.

Figure 1 is a perspective view of an aeroplane having my invention applied thereto.

Fig. 2 is a longitudinal sectional elevation of the discharge end of an exhaust conduit showing a preferred application of my spiral baffle plates and air-driven suction fan.

Fig. 3 is a cross-sectional view on the line 3—3 of Fig. 2, looking in the direction of the arrow.

Fig. 4 is a cross-sectional view on the line 4—4 of Fig. 2.

Fig. 5 shows a modified application of my invention.

The drawings show my invention applied to an aeroplane, where the muffling of the discharge of the exhaust gases is particularly important, though hitherto not attempted because of the loss of power to the engine. Fig. 1 indicates a conventional type of aeroplane, 1 and 2 representing the upper and lower planes respectively, 3 the body portion thereof, 4 the propeller blade, and 5 the internal combustion engine for rotating said

blade. 6 is an exhaust conduit for collecting the exhaust gases from the engine cylinders and carrying them rearward to discharge in such manner as not to interfere with the operator of the machine. I have shown this conduit raised and run over the top plane 1, where it is supported, as by a bracket 7; but it may evidently be differently located. In connection with this conduit 6, I employ, as shown, an exhaust fan located within the discharge end of said conduit and having radially projecting driving blades 15 which receive the full sweep of the air, during flight, to rapidly rotate said fan and cause a suction of the exhaust gases through said conduit.

Figs. 2, 3 and 4 are enlarged views showing a preferred construction of the outlet end of the conduit 6. 10 represents a suction fan, axially mounted as shown on an axle 11 supported in the hub portion 12 of a spider frame 13 fitted to the inner wall of the conduit 6 at the outer end thereof. The fan 10 is freely rotatable on the axle 11, and is held in place by a cap 14. This simple mounting of the fan illustrates my invention, but it is understood that in practice it may be desirable to use a different form of bearing to reduce friction and permit of the freer rotation of the fan. To rotate this fan I preferably employ radial extensions of the fan blades, which extensions are formed integrally with the latter and are offset, as shown, to project beyond the end of the conduit 6 and extend circumferentially around the same. These blades 15 form air contacting driving blades which are acted upon by the passing rush of air, during flight of the machine, and cause the suction fan 10 to rotate at a high rate of speed to force out of the conduit 6 the exhaust gases from the engine cylinder.

To muffle the sounds of the engine explosions I employ baffle plates 16, 16, 16, 16, within the conduit 6, which are preferably given a spiral twist as shown, to retard as little as possible the free exit of the exhaust gases and yet muffle their noise. These baffle plates may have varying pitches at different points in the length of the conduit to retard or advance the passage of the gases through the conduit, and they may be perforated if desired, as shown at 17, to afford communication from one spiral passage to another. The whirling motion given to the exhausting gases by the spiral

baffles 16, 16, 16, 16, causes said gases to rapidly pass to the exit end of the conduit, and this movement is insured by the rapidly rotating suction fan 10, which also distributes the exhaust into the air. The hub portion 12 of the spider 13 causes the exhaust gases to separate and pass through the fan blades nearer the outer circumference thereof where the momentum is greatest. If desired, a perforated screen, not shown, may be employed at the engine end of said baffled conduit to break the initial force of the explosion.

My exhaust suction fan may be employed, 15 as described, in connection with the spirally arranged baffle plates; or it may be used in connection with any of the well known types of mufflers; or both the spiral baffle plates and suction fan may be added to the exhaust 20 end of an ordinary muffler.

Fig. 5 shows a modified construction in which the fan 10^a is mounted in a cylinder 20 inclosing the end of the conduit 6, the fan being driven by the passing air through 25 said cylinder 20, and directly acting upon the exhaust gases in conduit 6 to draw them out; in this case the air rushing through the cylinder 20 tends to draw out the air in the conduit and assists the action of the fan.

30 Other modifications may be readily devised and I do not desire to limit myself to the specific construction shown and described. And it will be readily understood also that this device may be applied to other 35 motor driven vehicles.

My invention provides, in a simple and economical way, a muffler that will give the maximum effect of silencing the discharge of the exploded gases, with a minimum loss 40 of energy to the engine; and it is readily applicable to the exhaust conduit of any motor and requires no power from the engine to operate it.

What I claim is:—

45 1. In combination with an internal combustion motor driven vehicle having an exhaust outlet, an exhaust fan located at the discharge end of said outlet and adapted to be rotated by the passing air during motion 50 of the vehicle.

2. In combination with an internal combustion motor driven vehicle having an exhaust outlet, an exhaust fan located at the discharge end of said outlet and having extended driving blades adapted to be rotated by the passing air during motion of the vehicle.

3. In combination with an internal combustion motor driven vehicle having an exhaust outlet, an exhaust fan axially located 60 in the discharge end of said outlet, and having exhaust blades within said outlet, and exteriorly projecting air contacting driving blades.

4. In combination with an internal combustion motor driven vehicle having an exhaust outlet, an exhaust fan axially located in the discharge end of said outlet, and having a conical spreader head and exhaust blades within said outlet, and exteriorly projecting air contacting driving blades.

5. In combination with an internal combustion motor driven vehicle having an exhaust outlet, a spider frame within the discharge end of said outlet, an exhaust fan 75 axially mounted within said spider frame, and having exteriorly projecting air contacting driving blades.

6. In combination with an internal combustion motor driven vehicle having an exhaust conduit provided with a muffler, an exhaust fan located at the discharge end of said muffler and adapted to be rotated by the passing air during motion of the vehicle.

7. In combination with an internal combustion motor driven vehicle having an exhaust conduit, baffle plates within said conduit and an exhaust fan located at the discharge end thereof, said fan having air contacting driving blades.

8. In combination with an internal combustion motor driven vehicle having an exhaust conduit, spirally arranged baffle plates within said conduit and an exhaust fan located at the discharge end thereof, said fan 95 having air contacting driving blades.

9. In combination with an internal combustion motor driven vehicle having an exhaust conduit, spirally arranged baffle plates within said conduit and an exhaust fan axially mounted in the discharge end thereof, said fan having exteriorly projecting air contacting driving blades.

10. In an aeroplane having an internal combustion propeller-driving engine, an exhaust conduit from said engine extended rearward over a plane thereof, spirally arranged baffle plates within said conduit and an exhaust fan at the discharge end thereof having radially extending air contacting 110 driving blades.

In testimony whereof I affix my signature.

HENRY F. LOOMIS.
